United States Patent Office

Des. 229,464

Patented Dec. 4, 1973

229,464

STACKABLE CHEST OF DRAWERS

Alfredo Martini, Via della Giardina, Monza, Italy

Filed Oct. 12, 1970, Ser. No. 25,474

Term of patent 14 years

Int. Cl. D6—04

U.S. Cl. D6—165

Fig. 1

Fig. 2

FIG. 3

FIG. 4

FIG. 1 is a top view of the chest of drawers according to the design with drawers partially open;

FIG. 2 is a side elevational view of the chest of drawers in FIG. 1 with a portion cut away.

FIG. 3 is a front perspective view and

FIG. 4 is a rear perspective view.

I claim:

The ornamental design for a stackable chest of drawers, as shown.
